UNITED STATES PATENT OFFICE.

CHARLES ALISON KEE, OF GLASGOW, SCOTLAND, ASSIGNEE OF ONE-THIRD TO ANDREW WILSON AND ONE-THIRD TO WILLIAM ALISON KEE, OF GLASGOW, SCOTLAND.

ENGRAVING-MACHINE.

1,079,559.

Specification of Letters Patent.

Patented Nov. 25, 1913.

Application filed February 6, 1911, Serial No. 608,904. Renewed September 27, 1913. Serial No. 792,232.

To all whom it may concern:

Be it known that I, CHARLES ALISON KEE, a subject of the King of Great Britain, residing at Glasgow, Scotland, have invented 5 certain new and useful Improvements in Engraving-Machines, of which the following is a specification.

This invention relates to a machine for engraving or etching metallic surfaces and 10 is especially adapted for use in the engraving or etching of copper rolls for calico and other printing.

The machine is capable of dealing with a number of metallic surfaces, such as copper 15 rolls, simultaneously.

With this machine I may proceed by first engraving a design or pattern on a printing plate and then, after inking the plate with a greasy and acid-resisting ink, transfer im- 20 pressions from the plate to the copper roll which is subsequently engraved or etched in the usual manner, the raised or relief parts of the printing plate forming clear or un- 25 inked parts on the roll, the other parts being inked, so that, when etching, the acid only bites into the said clear or uninked parts of the roll and so reproduces the de- 30 sign. Or I may proceed by first "marking on," or making a light impression of the de- 35 sign or part of the design, on the surface of the copper roll by means of a mill which is engraved with the design to be reproduced, and the roll can, thereafter, be removed 40 from the machine and completely engraved or etched in the usual manner the "marking on" insuring that all the rolls shall be correctly engraved and "misfits" prevented. Under either method of procedure I can, 45 by means of this machine, deal with a number of copper rolls or other metallic surface, at one time thereby effecting great saving in time and labor.

In order that the invention may be clearly understood I have hereunto appended ex- 50 planatory drawings, whereon:-

Figure 1 is a side view of a machine adapted to deal with four copper rolls simultane- 55 ously. Fig. 2 is a sectional view taken on the line X-X, Fig. 3 the upper part of the machine being removed. Fig. 3 is an end view of the complete machine, looking on the left-hand end of Fig. 1. Fig. 4 is a plan view of the machine with the brackets 6 and the parts connected therewith, removed. Fig. 5 is a cross section and Fig. 6 a longi-

tudinal section of one of the boxes 31. Fig. 7 is a detail side view of one of the mills for use when "marking on." It is shown in engagement with a copper roll. Fig. 8 is an end view of the same. Fig. 9 is an end view of the variable speed gear for moving the frame.

The machine is made with a pair of side cheeks or frames 1, 2, each having thereon four upward extensions or brackets 4 within each of which there is provided a bearing for one end of a screwed spindle 5. The spindles 5 have blocks 5^a adjustably screwed thereon and between these blocks the copper rolls 3 are mounted as usual. Secured upon 70 each of the extensions 4 is a bracket 6 having therein a vertical slot or opening 7 from top to bottom of which there extends a screw 8, and on the upper end of the screw there is secured a bevel wheel 9. Secured on the 75 bracket 6 are bearing brackets 10 carrying horizontal spindles 11 upon which are bevel wheels 12 in mesh with the bevel wheels 9, and each spindle 11 has, on one end thereof, a hand wheel 13 by means of which the spindles 11 may be rotated in such manner as to rotate the vertical screws 8 at the opposite ends of any of the copper rolls 3 simultane- 80ously and, located above each copper roll 3 and parallel thereto, is a cross beam 14 hav- 85 ing recesses therein for the reception of small wooden wedges 15 which bear on the roll 3 and hold same rigidly in position and, formed on each end of the beam 14 is a nut or screwed sleeve 16 through which passes 90 one of said vertical screws 8 in such manner that the cross beam 14 may be raised or lowered by means of the hand wheel 13 and bevel gear hereinbefore described. The 95 beams 14 may thus be readily adjusted to suit copper rolls of varying diameters.

Located between the side cheeks or frames 1, 2, is a vertically adjustable bed 17 which is supported by four vertical screws 21 whose screw threads engage the threads of screw 100 sockets 21^a on the frames 1, 2. The screws are provided with worm wheels 18 adapted to be operated by means of a hand wheel 19 and shaft 19 through worm and bevel gear 20 suitably mounted in bearing brackets de- 105 pending from the bed or base 17 in such manner that on the hand wheel 19 being rotated the bed 17 can be raised or lowered by turning the screws 21.

Mounted on the bed 17 so as to be capable 110

of sliding transversely of the machine is a table 22 which is provided, on its underside, with depending guides 23 adapted to slide on the surfaces 23^a (see Fig. 2) of the bed 6 17, and projecting upward from the table 22 are two sets of bearings 24 each pair carrying a shaft 24^a with wheels 25 thereon upon which the frame 26 rests and is capable of a 10 sliding movement longitudinally of the machine. The table 22 is traversed transversely of the machine by means of a nut 27 which depends therefrom and works upon a horizontally arranged screwed spindle 28 mounted in end bearings in the bed 17 and 15 having on one end thereof an index wheel 29 made with peripheral teeth and having an index pointer 30 secured pivotally adjacent thereto. The frame 26 is traversed, upon the wheels 25, longitudinally of the machine, 20 in the manner hereinafter described.

Slidably fitted in the frame 26 and between cross pieces 26^a therein (see Figs. 5 and 6) are four boxes 31 which may each be moved vertically so as to bring a printing 25 plate 32 therein into or out of engagement with a copper roll, there being provided in the frame 26 a longitudinal shaft 57 having a series of cams 58, one beneath a plate 31^a slidably fitted in each box 31. The boxes 31 30 are preferably square. Bearing against the upper side of the plate 31^a of each box is a cam 32^a on a spindle 33 rotatably carried in the box and capable of being turned by a key passed through a hole 26^b in the frame 26. 35 On the end of the shaft 57 is a lever 59 from whose end a weight 60 is hung so as to normally rotate the shaft 57 into such a position that the cams 58 push up the boxes and retain all the printing plates 32 in close 40 engagement with the copper rolls. Should slight adjustment be required for any particular plate 32 it can be effected by manipulating its cam 32^a.

The spindles 5 at one side of the machine 45 are each provided with a worm wheel 33 and located beneath the worm wheels 33 is a worm shaft 34 carried in bearing brackets 35 on the side frame 1 and engaging each wheel 33 is a worm 36 on the shaft 34, which is 50 provided with a hand wheel 37 by means of which the rolls may be all rotated simultaneously by hand for the purpose of adjustment and, in adjusting the rolls in a rotary direction accuracy of position for printing 55 or marking on is insured by means of an index wheel 38 secured on the end of one of the roll spindles 5, a swiveling pointer 39 being pivotally carried on the frame 1 adjacent thereto. For rotating the rolls, 60 when desired, by power, the shaft 34 has at its end, a bevel wheel 41^a which gears with a bevel wheel 41 carried in a bracket 41^b (Fig. 4). On a short sleeve 43^a is keyed a belt pulley 40 and a bevel wheel 43^b having a collar with which the forked end of a lever 42^a

fulcrumed on the bracket 41^b engages. By manipulating the rod 42 the bevel wheel 43^b can be put into and out of engagement with the wheel 41 and in this manner the power drive can be put into and out of engagement with the wheel 41 and in this manner the power drive can be put on or taken off. 70

For traversing the frame 26 beneath the rolls at a speed exactly equal to the surface speed of the copper rolls variable speed gear is provided for moving the frame so that the machine can be used for rolls of different diameters. To this end there is slidably keyed on the shaft 34 a bevel wheel 43 which can be caused to gear with and drive a bevel wheel 41^c by means of the rod 65 and lever 65^a. The wheel 41^c is on the upper end of a feathered shaft 45 mounted in bearing brackets 46 on the frame 1 and on this shaft 80 85 45 is a worm 47 which engages and drives a worm wheel 48 whose shaft 49 is mounted in bearings in extensions 50 of the bed 17 (see also Fig. 9). The worm 47 is held in position on the shaft 45 by brackets 51 on one extension 50. 90

Carried in the extensions 50 is a slide 53 which is made on its upper side with a dovetail 54 upon which slides a block 55 having a screw whereby it may be clamped to the slide 53. The slide 53 has a depending bracket 52 with a nut through which the screwed shaft 49 extends. Pivoted in the block 55 is a channeled block 56 within the groove or channel of which works a bar 61 100 pivotally connected to the underside of a winged extension 62 on the frame 26, the bar 61 being made with pins 63 which extend upward through curved slots 64 in the extension 62 and which may be graduated or 105 marked so that the pins 63 serve as indicators whereby the angle made by the bar 61 with the line of movement of the frame 26 may be ascertained. The pins would be provided with clamping nuts 63^a. The bar 61 110 is adjusted to the desired angle, to give the required travel of the frame 26 with the boxes 31 therein and is then clamped by the nuts 63^a. When the screw 47 is rotated the slide 53, block 55 and channeled block 56 115 are moved transversely with the result that the bar 61 and frame move longitudinally. By altering the angle which the bar 61 makes with the line of travel of the frame 26, the travel of the said frame may be varied as will be readily understood, and when the bar 61 is placed at exactly 90° to the said line of travel no motion is imparted to the frame 26. When it is desired to traverse the table 22 transversely of the machine by means of the traversing screw 28 the sliding block 55 is unclamped from the slide 53 so as to be free to slide longitudinally thereof and on the completion of the transverse adjustment or movement the slide 53 and slid- 120 125 130

ing block 55 are again clamped together ready for operation. When it is desired to throw this variable speed gear out of operation the controlling rod 65 is manipulated so as to move the bevel wheel 43 out of gear with the bevel wheel 41 on the shaft 45.

When it is desired to use the machine for "marking on" the printing plates 32 are removed from the boxes 31 and are replaced by plates 66 each of which has mounted thereon (see Figs. 7 and 8) a pair of brackets 67, 67 for the spindle 68 of the mill 69 used for "marking on" the design or a portion of the design on the copper roll and secured on one end of the spindle 68 is a double armed lever, the one arm 70 of which is normally pulled downward by the action of a spiral spring 71 while the opposite arm 72 is pressed against a stop block 73, the arrangement being such that, in operation, the mill 69 is rotated by its roll 8, rotating against the action of the spiral spring 71, and, on the aforesaid weighted lever 59 being raised so as to turn the cams 58 downward the mills are lowered away from the copper rolls and on being thus released are automatically turned back by the action of the springs 71 until the arm 72 comes in contact with and has its motion arrested by the stop blocks 73. When the machine is being used for "marking on" as above described the gear for reciprocating the frame 26 is out of operation and the frame 26 can be held in position with the mills directly beneath the copper rolls by simply moving the bar 61 to a position at right angles to the said frame. With the bar 61 clamped at right angles to the line of travel of the frame 26 the worm and screw gear for driving the frame may be allowed to remain in operation as the bar 61 slides in the channel block 56 without imparting any motion to the frame 26. The worm and screw gear for operating the frame traversing gear is however, preferably thrown out of gear during the "marking on" process, the bevel wheel 43 on the shaft 41 being moved by means of the rod 65 out of mesh with the bevel wheel 41.

If so desired for locking the frame 26 in place there may be provided thereon means preferably consisting of a hinged bar capable of engaging socket or like parts suitably arranged on the table 22.

In operation, with a machine for engraving or etching copper rolls for calico or other printing, the printing plates 32 having been placed in position in the boxes of the frame 26 and having been inked, and the table 22 having been moved transversely of the machine by means of the screws 12 into its correct position at the ends of the copper rolls, the weight 60 is allowed to act on the lever 59 in such manner as to raise the printing plates 32 into contact with

the copper rolls, and the machine is then set in operation, all the rolls being rotated simultaneously and in the one direction through the worm gear and the frame 26 being traversed longitudinally of the machine 70 at a speed corresponding with the surface speed of the rolls, the speed of travel of the frame 26 being exactly equal to the surface speed of the copper rolls so that no slip takes place between the printing plates and the copper rolls. The frame is traversed 75 through the worm gear 32, 36, and screw and nut gear 49, 52, and through the bar 61 which latter would be previously adjusted to suit the particular diameter of rolls being 80 dealt with. On the completion of the printing of one part of the rolls, the machine is stopped, the boxes 31 lowered, by manipulating the cams 58, and the table 22 shifted so as to bring the printing plates under a 85 fresh part of the rolls when the boxes are again raised by the cams 58 the printing plates contacting with a fresh portion of the rolls which latter are thereupon again rotated simultaneously. Usually only a 90 part of the circumference of the rolls is printed at a time, the index wheel 38 registering the amount precisely, so that the next repeat in the circumference of the design can be fitted exactly. For four or more 95 color printing each roll is printed with its own design and as the designs are all printed simultaneously on the rolls, which latter all move at exactly the same speed, it follows that the designs must all register exactly 100 thereby obviating "misfits."

When it is desired to use the machine for "marking on" in connection with mill engraving the printing plates 31 are removed from the frame 26 and are replaced by the 105 plates 66 carrying the mills and on the frame 26, whose traversing gear is put out of operation, having been moved both transversely and longitudinally into the correct position at the ends of the rolls, and having 110 been clamped the mills are raised by means of the lever 57 and cams 58 into engagement, with the rolls. The copper rolls are then simultaneously rotated through a small 115 angle by means of the worm gear thereby causing the design, in cameo on the mills, to be marked on the copper rolls and the mills are then moved away from the rolls by lowering the boxes 31 and thereupon immediately spring back to their original position ready for the next "marking on." As 120 in the printing operation, the rolls are rotated and the table 22 is traversed until the operation is completed.

Having now fully described my invention 125 what I claim and desire to secure by Letters Patent is—

1. In combination, a frame, means for carrying a plurality of pieces of work in the frame, means for holding the pieces of work 130

- in the frame, means for raising and lowering the bed, a table on the bed, means for moving the table transversely on the bed, a frame on the table, a pivoted bar operatively connected with the frame, a channeled block carrying said bar, a guide for the block, means for moving the guide and block transversely of the machine, and means carried by the frame for making impressions.
- 10 13. In combination, a frame, a bed carried in the frame, means for raising and lowering the bed, a table on the bed, means for moving the table transversely on the bed, a frame on the table, a movable bar operatively connected with the frame, a channeled block pivotally carrying said bar, a guide for the block, means for moving the guide and block transversely on the machine, and means carried by the frame for making impressions.
- 15 14. In combination, a frame, a bed carried in the frame, means for raising and lowering the bed, a table on the bed, means for moving the table transversely on the bed, a frame on the table, a movable bar operatively connected with the frame, a channeled block carrying said bar, a guide for the block, screw means for moving the guide and block transversely of the machine, worm gear for operating the screw, means for throwing the worm gear into and out of operation, and means carried by the frame for making impressions.
- 20 15. In combination, a frame, a bed carried in the frame, means for raising and lowering the bed, a table on the bed, means for moving the table transversely on the bed, a frame on the table, a movable bar operatively connected with the frame, a channeled block carrying said bar, a guide for the block, screw means for moving the guide and block transversely of the machine, and means carried by the frame for making impressions.
- 25 16. In combination, a frame, a bed carried in the frame, means for raising and lowering the bed, a table on the bed, means for moving the table transversely on the bed, a frame on the table, a movable bar operatively connected with the frame, a channeled block carrying said bar, a guide for the block, screw means for moving the guide and block transversely of the machine, worm gear for operating the screw, means for throwing the worm gear into and out of operation, and means carried by the frame for making impressions.
